UNITED STATES PATENT OFFICE

HARRY W. DUNN, OF BROOKLYN, NEW YORK

DARK ROOM SHADE CONSTRUCTION

Application filed February 2, 1929. Serial No. 337,079.

The invention has for an object to effect improvements in shade constructions especially designed to enable the exclusion of daylight from a room which at other times requires open windows. It is also an aim to present a structure of this kind which will enable the ready ventilation of the windows equipped with my invention when the parts are in position for the exclusion of light. Another important object is to present a novel operating arrangement whereby proper functioning of the shade may be assured and the shade maintained peculiarly in operative relation to a cooperating frame and guideways. A further important aim is to provide a novel construction of the means for guiding the shade and maintaining it against displacement by air currents, to the end that such retaining and guide devices may be readily attached to ordinary shade material in a practical manner and with a minimum of difficulty. A still further object is to coordinate the guide members attached to the edge portions of a shade so that they may be readily rolled upon a spring roller without interference of the guide members with the winding or unwinding of the shade or damage to material of the shade by reason of the superposition of the several guide elements attached thereto.

A further important object of the invention is to present a unit shade and frame assembly adapted to be attached to or incorporated in any window of ordinary construction so that it may be darkened as required. A further important aim is to present operating means which will leave the opening of the window entirely clear when the shade is in open position and which will cause movement of the shade efficiently to various extended positions, without distortion.

Additional objects, features of invention, and advantages reside in the construction, arrangement and combination of parts as will be more readily understood from the following description and accompanying drawings, in which

Fig. 1 is an elevational view of a window

constructed in accordance with my invention, with the front casing partly broken away.

Fig. 2 is a vertical edge view of the structure.

Fig. 3 is a fragmentary vertical section on the line 3—3 of Fig. 1. 55

Fig. 4 is an end view of the roller with the shade wound thereon.

Fig. 5 is a horizontal section midway of the frame. 60

Fig. 6 is an enlarged fragmentary sectional view of one edge portion of the frame and shade showing the guide clip.

Fig. 7 is a fragmentary section on the line 7—7 of Fig. 1. 65

Fig. 8 is a detail view of the shade and stick, and cord connections.

Fig. 9 is a cross section of the stick.

There is illustrated a framing 10 which may comprise a part of, or may be attached to, a window frame being substantially rectangular in form with a clear opening therethrough adapted to be aligned with the window opening for the passage of light and air. The frame includes a boxing 11 at the upper part adapted to enclose a shade roller 12, which may have a familiar bracket mounting on the side members 13 of the frame. The side members 13 comprise deeply channelled members (each having a removable front board 14); and a bottom cross member 15 is similarly formed. The boxing 11 is formed with an outlet slot for the shade material 16 wound upon the roller, the channels 13' of the side members of the frame being aligned 70 75 with the slot. 80

The channels in the side members of the frame are preferably coated with a drop black in order to minimize reflection of light, and their front and rear sides are spaced apart sufficiently to provide a clearance for passage of air between the sides of the channels and the shade. In the bottom of the groove of each side member of the frame there is secured a metal guide channel member 17, substantially U-shaped in cross section with the edges at the open side inturned, so as to provide a slot 18 materially narrower than the corresponding interior measurements of the guide 17. The slot 18 is en- 85 90 95 100

larged at the upper end of the guide, having edge portions longitudinally divergent to the full measurement of the guide, and the front side of the guide 17 is formed with an extension 19 in the form of a tongue forming a continuation of the adjacent edge portion of the slot 18 in the guide, and inclined so as to engage and guide the clips 20 of the shade into the channel, as will be described.

10 It should be noted that the slot from the roller boxing 11 and the corresponding channel guide members of the frame are offset from the axis of the roller so as to facilitate entrance of the shade to the channel of the

15 guide device.

The shade material is customarily of a heavy rubberized fabric, and fixed thereupon on each edge at longitudinally spaced intervals there are guide clips 20 which project laterally beyond the edge of the shade a distance, and each has a T-shaped head thereon adapted to enter the guide 17 and engage across the slot 18 therewith so as to prevent the clip from being drawn from the guide.

20 Each clip comprises a bifurcated member of sheet metal formed of a single strip of stock bent inwardly upon itself closely adjacent and on each side of the middle of the blank, then bent outwardly at right angles to the underlying portion in close abutting relation, so as to form arms 22 to readily receive the edge of shade material therebetween. These arms are secured together by a rivet or other means at 23 spaced a distance from the head

25 21, and still further outward on the arms they are provided with registered openings which receive rivets 24 by which they are secured upon the intervening part of the shade when it is inserted between the arms. The material of the strips is comparatively thin sheet metal so that they do not bulk large, but it is desirable to so space the clips on the shade when secured thereto that the distance between any two of them is more or less than

30 45 the circumferential measurement on the outer face of the adjacent shade material to the next preceding clip.

It is also important to note that the shade material stops short of the guides 17 a distance at least equal to the space between the shade material and the front and rear faces of the channels 13' of the side members 13, and the clips are so arranged on the shade that they will engage to prevent material lateral movement of the shade between the guides 17. If desired, the clips may of course be formed as members extending entirely across the shade, but it has not been found necessary. By reason of the construction presented, the shade is held medially spaced between the front and rear sides of the dark channels in the side members of the frame so that air can pass freely around the sides of the shade when it is closed, effecting thorough ventilation, notwithstanding the

fact that the room within the window is completely darkened.

In order to effect certain movement of the shade into closed position, so that neither edge portion will be higher than the other, and thereby liable to admit light, and also in order to effect an even draft on each side of the shade when it is operated, means for moving the shade are provided consisting in a shade stick 25, slightly thicker than the ordinary shade stick, and mounted in each end between suitable cheek plates 26 pulleys 27 and the stick is formed with a longitudinal channel 28 in the upper edge alined with the upper edges of the pulleys. A cord 29 is slidable in the channel, passing downwardly at the outer side of the pulley at each end of the stick. The cheek plates comprise substantially U-shaped members having bight portions located longitudinally outwardly of the ends of the stick. The channel 28 may be formed by continuing the cheek plates entirely throughout the length of the stick, with the upper edges of the plates projecting above the stick, as in Figure 8, or the upper edge of the stick may be grooved for the purpose. By reason of the fact that the upper part of the loop in the shade material is drawn above the shade stick by the weight of the stick and the draft of the cord thereon complete clearance for the movement of the cord freely in the channel is assured.

The cord 29 has one end secured at 30 in the lower left hand corner of the frame closely adjacent the guide 17 within the dark channel 13' of the frame. The other end portion of the cord is extended downwardly from the shade in the opposite dark channel of the frame and passed outwardly through the front side of the frame, a suitable opening 32 being there provided with an escutcheon plate 33 secured to the face of the frame and having a pulley 34 for the cord mounted on a suitable bracket on the inner side of the plate in a vertical plane at right angles to the plate. The bracket 35 fits closely around the pulley at the inner side thereof so as to form a guide for the cord as the cord from the shade enters the pulley groove, preventing displacement of the cord from the pulley. The arrangement of the bights of the members 26 in a similar relation on the shade stick also assures retention of the cord in proper engagement with the pulleys 27. A cleat 36 is also fixed on the escutcheon plate above the exit opening for the cord, so that the cord may be secured in adjusted positions. Other securing means may be used, however, and it is also contemplated that metal tapes or other flexible members may be used instead of cord and reeling and unreeing devices associated therewith instead of requiring hand operation, if desired.

The shade roller 12 is preferably a spring

roller without dogs engaging the trunnion to check rotation of the roller, so that the roller is always tending to rotate to reel or wind the shade material thereon, and is opposed by the cord 29. By reason of the arrangement of the cords, shade stick and the connection of the cord on the frame, draft upon the projecting end portion of the cord will cause an equal downward pull at each side 5 of the shade, so that the heads of the clips will not be caused to bind in the guide, neither side of the shade will be pulled downward excessively, and distortion of the form of the shade will thus be avoided. It may 10 be readily understood that with a number of clips secured upon the shade material as shown, anything tending to produce more pull at one side than the other would cause the clip portion to pack into the material of 15 the shade and allow the adjacent lower edge of the shade to pull downwardly further than the opposite edge, and in addition the lower body portion of the shade be caused to swing laterally so that the clip devices would 20 bind in the guide. Faulty operation of the shade would result in various other ways, not the least of which is the liability of ingress of light by reason of one side of the shade being higher than the other when the 25 parts are in closed position.

In the operation of the device, it will be readily understood that to lower the shade it is simply necessary to pull upon the cord 29 until the shade is drawn downwardly to the 30 desired extent, when the cord may be secured upon the cleat 36 to hold the shade as adjusted. As the roller unwinds, the clips moving therefrom initially tend to engage the side of the guide channel 18 next the outer side of the window, and as more material is unwound, the clips will engage the inner edges of the channel 18 and the guide tongue 19, so that they will move with certainty into the guide 35 17.

40 In case a heavy wind should blow against the shade, the heads of the clips will prevent the edges of the shade from being drawn out of the dark channels of the side members 13 of the frame, and will also tend to hold the shade equally spaced between the front and back sides of the dark channel, so that air may 45 pass inwardly at one side of the shade, between the shade and the frame, thence around the lateral edge of the shade, and outwardly 50 through the space between the shade and the side of the dark channel opposite the point of entrance of the air.

I claim:

55 1. A window-attachable room darkening appliance comprising a frame adapted to be secured over a window opening and having a roller and attached shade mounted thereon, the sides of the frame comprising spaced front and rear members forming exceedingly deep darkening channels as compared to prior

shade constructions, substantial edge portions of the shade being engaged therein but spaced from the innermost parts of the channels, and a roller housing forming a continuation of the darkening channels, means to center the shade in the opening and to center the edge portions of the shade between the front and rear members in said darkening channels whereby to form an air way between the shade and frame parts, a shade stick mounted at 70 the outer end of the shade, pulleys at the ends of the stick, a cord anchored to the bottom of the frame at one side in the darkening channel, and extended upward over the pulley at the adjacent end of the stick, thence longitudinally of the stick and downwardly over the opposite pulley thereon, and in the darkening channel to the bottom of the frame, an opening in the front of the frame opening on the darkening channel at the last mentioned point, and means included thereon 75 operatively associated with said opening to operate the cord and hold it at adjusted positions.

2. A dark-room window shade structure 90 comprising a frame having a window opening therethrough, the frame having exceedingly deep darkening channels in the sides thereof as compared to the prior practice in shades, a roller housing included in the frame forming a continuation of the channel, a roller and shade mounted therein positioned to unreel substantially wide edge portions of the shade to the channels, means to operate the shade, guide devices at the sides of the frame located in the channels and having slots much smaller than the interiors of the channels, and shade centering members carried on the edge portions of the shade constructed to space the shade from the guides and from the sides of the channels to form ventilating air ways around the shade.

3. A dark room window shade construction comprising a frame, a roller mounted therein, a shade attached to and adapted to be wound on the roller, said frame having sides formed with channels adapted to, and receiving the edge portions of the shade in light-excluding relation, a closed housing for the roller forming a continuation of the frame and in light-excluding relation to the shade, said frame including also a bottom portion having a deep channeled light-excluding part to receive and coact with the lower edge portion of the shade in light-excluding relation, and means to operate the shade including flexible draft means extending into the lower part of the frame.

4. In a device of the character described, a deep channel and an opaque shade material having an edge portion of substantial width slidably therein, a guide channel at the inner part of the deep channel having a narrow slot in the medial plane of the deep channel, a headed member having its head portion in 125 130

the guide channel and a shank portion projected outwardly through the slot, said edge portion of the shade being fixed upon the shank spaced from the guide slot, to center the shade in the deep channel and space said edge portion similarly from the guide slot.

In testimony whereof I affix my signature.

HARRY W. DUNN.
